ATTORNEY

UNITED STATES PATENT OFFICE.

CHARLES R. BROWN, OF DETROIT, MICHIGAN.

SLIDING-DOOR LOCK.

1,264,364.

Specification of Letters Patent. Patented Apr. 30, 1918.

Application filed October 3, 1916. Serial No. 123,570.

To all whom it may concern:

Be it known that I, CHARLES R. BROWN, a citizen of the United States, residing at Detroit, in the county of Wayne and State 5 of Michigan, have invented certain new and useful Improvements in Sliding-Door Locks, of which the following is a specification.

The present invention has reference, generally, to improvements in locks; and, the 10 invention relates, more particularly, to a novel sliding car door lock.

The invention has for its principal object to provide a sliding door lock, which will be automatically actuated upon the closing of 15 a door to which the same is attached, thereby, preventing the opening of the door by unauthorized persons and preventing loss of the car contents.

Among other aims and objects of the invention may be recited, the provision of a 20 lock of the character mentioned with a view to compactness, and in which the number of parts are few, the construction simple, the cost of production small, and efficiency and 25 operation high.

The invention also includes a novel means, whereby, access to the lock, after the same has been moved into locking position, will be prevented, thus, defeating any attempts 30 as may be made to tamper with the lock.

Other and further improvements and 35 novel details in the construction and arrangement of parts will be appreciated from the description to follow which for a clear 40 understanding of the invention should be considered in connection with the accompanying drawings, forming a part hereof and wherein a preferred embodiment of the invention is shown for the purpose of illustration.

In the drawings:

Figure 1 is a perspective of the improved sliding door lock as applied, and

Fig. 2 is a perspective of the sealing means 45 whereby tampering with the lock will be prevented.

Referring now more particularly to the drawings, wherein like reference numerals 50 designate corresponding parts throughout the several views, I have shown by way of illustration, the improved lock as applied to the conventional form of freight car, wherein a fragment of the car body is indicated by the numeral 2 and a fragment of the sliding 55 door, by the numeral 1. With more especial reference to the present improvements, there

is arranged upon the car door 1, a substantially U-shaped bracket 3, the said bracket being secured in position by passing rivets or the like 4 through the adjacent leg portion 60 thereof into the car door. The outer end or leg portion of the bracket 3 is diagonally arranged, as indicated by the numeral 5 and has formed therein adjacent its lower extremity, a bearing opening 6, the purpose of 65 which will be presently apparent. A second diagonally positioned leg 7 is affixed to the under face of the body portion of the bracket 3 and is arranged complementary to the leg portion 5, a suitable bearing opening being 70 formed in the lower extremity thereof and preferably, in horizontal alinement with the bearing opening 6. A cylindrical element 8, having trunnions 9 formed upon the ends 75 thereof is received between the supporting legs 5 and 7, the trunnions 9, obviously, being inserted within the bearing openings of the said leg portions. That trunnion, as adjacent the car door 1, is provided with a squared extension 10, whereby the same may 80 be engaged with a suitable implement and the cylindrical element 8 thereby turned. To facilitate the passing of the implement through the car door 1 into engagement with the squared extension 10, an opening 11 is 85 formed therein and is alined with the said extension, thus, offering what may be termed 90 a keyhole. A right angularly disposed arm 12 is formed upon the cylindrical element 8 and has its outer end bent at angles, to provide a catch 13, this catch serving as the locking means, whereby, the car door 1 will 95 be held in locked position. A depending leg 14 is formed upon the opposite side of the cylindrical element 8, preferably in alinement with the angularly disposed arm 12 and affords tripping means, whereby the 100 said arm will be automatically actuated.

The car frame 2 has arranged upon the inner side thereof, adjacent its forward end, a keeper plate 15 which has formed therein, intermediate its ends, an annular opening 16. The rear end of the keeper plate 15 is provided with an angularly bent leg 17, the leg serving as means whereby the keeper plate 105 may be secured to the frame 2, by rivets 18 which are passed therethrough into the said frame. It will be noted upon reference to Fig. 1, that the keeper plate 15 projects forwardly of the adjacent marginal edge of the 110 door 2.

With a view toward providing means

whereby the opening or keyhole 11 may be guarded, that is, provided with means which will prevent the insertion of various implements therethrough in an effort to operate 5 the catch 13, the cover plate 18 is pivotally connected with the outer side of the car door 1, as at 19 and carries upon its lower portion, an angularly disposed apertured lug 20, which, when in its lowermost position 10 will align with a similar lug 21, affixed to the car door by the fastening 22. By so aligning the apertured lugs 20 and 21, a wire 23 may be readily passed therethrough and the ends thereof engaged with a suitable 15 form of seal, as is indicated by the reference character 24. By this means, an efficient anti-tampering device is afforded.

The operation of the construction may be reviewed as follows:

20 Assuming that the car door 2 is in open position it is desired to close the same, it is of course moved laterally within its track ways as arranged within the freight car doorway. As the same approaches its limit 25 of lateral movement, the outer end of the keeper plate 15 will engage the depending leg 14, causing the cylindrical element 8 to be rotated, consequently, overbalancing the arm 12 and permitting the same to be swung 30 downwardly, whereupon, the catch 13 will be engaged with the annular opening 16 in the keeper plate. Thus, reopening of the door will be prevented, that is, by merely applying a reverse push thereto. The cover plate 18 is now swung downwardly over 35 the keyhole 11 and a sealing wire 23 passed through the aligned aperture lugs 20 and 21 and a seal of some sort engaged therewith. To open the door, the seal 24 is of 40 course, broken and the cover plate 18 then swung upwardly from the keyhole 11. At this point, a suitable turning implement or key is inserted through the keyhole and the end thereof engaged with the squared extension 45 of the adjacent trunnion of the cylindrical element 8, whereupon, it is turned and causes the cylindrical element 8 to be rotated, hence, the arm 12 carrying the catch 13 to be raised into position as 50 shown in the Fig. 1. When in raised position, the arm 12 will rest upon the adjacent marginal edge of the body portion of the bracket 3 and will remain so until again actuated by the keeper plate 15. The 55 door 2 may now be readily slid to open position and the key removed from the keyhole 11.

Still further embodiments of the invention and the one herein especially defined 60 may be resorted to as conditions or preference may dictate, as may be in keeping with the hereto appended claims.

I claim:

1. A door lock, including, in combination 65 with a sliding door and a frame therefor, a

keeper carried by the frame and extending beyond the forward marginal edge thereof, a bracket secured to the inner side of the door and having a plurality of spaced apart diagonally disposed supporting legs formed 70 thereon, a catch pivotally mounted between said supporting legs, a depending leg formed upon said catch, the catch being adapted to normally rest upon the body portion of the bracket when in inoperative position, 75 said keeper engaging the depending leg when the door is slid to closed position, whereby, to cause the catch to be swung into locking engagement with the keeper, means arranged upon the catch for facilitating the engaging of a turning implement therewith for moving the same into unlocked position, and guard means arranged upon the outer side of the frame for preventing fraudulent operation of the catch. 80 85

2. A device of the class described, a combination of a frame and a sliding door therefor, a bracket carried by said door, a catch pivotally mounted upon said bracket, a depending leg formed on said catch, an arm projecting from said catch and normally bearing on said bracket, whereby the movement of said catch will be limited in one direction, a keeper carried by said frame, said depending leg being attached to engage said keeper for preventing the movement of said door in one direction and means for facilitating the movement of said latch for swinging said leg from engagement with said keeper. 95 100

3. In a device of the class described, a combination of a frame having a sliding door, a keeper carried by said frame, a bracket secured to said door and having a plurality of spaced legs, a cylindrical shaft 105 pivotally mounted upon said legs, a depending leg carried by said shaft, said depending leg being adapted to engage said keeper for holding said door against unauthorized movement, means for facilitating the turning of said shaft, and means for limiting the turning of said shaft in one direction. 110

4. In a device of the class described, the combination of a frame having a sliding door, a keeper carried by said frame, a bracket carried by said frame, a bracket carried by said door, said bracket having a plurality of spaced legs, a shaft having trunnions projecting therefrom, said trunnions being pivotally mounted upon said 120 legs, a depending leg carried by said shaft, an angularly projecting arm carried by said shaft, said arm being adapted to engage said bracket for limiting the rotary movement of said shaft in one direction 125 and said depending leg releasably engaging said keeper for holding the door against movement.

5. In a device of the class described, the combination of a frame having a sliding 130

door, a keeper carried by said frame, a bracket carried by said frame, a bracket carried by said door, said bracket having a plurality of spaced legs, a shaft having 15 trunnions projecting therefrom, said trunnions being pivotally mounted upon said legs, a depending leg carried by said shaft, an angularly projecting arm carried by said shaft, said arm being adapted to engage said bracket for limiting the rotary movement of said shaft in one direction,

said depending leg releasably engaging said keeper for holding said door against movement and one of said trunnions being squared, whereby means may be attached thereto for turning said shaft.

In testimony whereof I affix my signature in presence of two witnesses.

CHARLES R. BROWN.
